[57] CLAIM

The ornamental design for telephone set, as shown and described.

DESCRIPTION

FIG. 1 is a front, top and right side perspective view of a telephone set showing our new design in cradled relationship;

FIG. 2 is similar perspective view of the stand, and a perspective view of the handset inverted and space apart for clarity of illustration;

FIGS. 3 and 4 are respectively top and bottom plan views thereof;

FIGS. 5 and 6 are respectively front and rear elevational views thereof; and

FIGS. 7 and 8 are respectively left and right side elevational views thereof.

The showing of cord in sundry views is for convenience of illustration.
